UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,362,592.

Specification of Letters Patent. Patented Dec. 21, 1920.

Application filed November 21, 1917. Serial No. 203,081.

To all whom it may concern:

Be it known that I, JOHN H. BELL, a citizen of the United States, residing at South Orange, in the county of Essex and State of New Jersey, have invented certain new and useful Improvements in Telegraph Systems, of which the following is a full, clear, concise, and exact description.

This invention relates to telegraph systems, and more particularly to duplex telegraph equipments.

The principal object of this invention is to provide an improved system whereby the condition of balance on duplex circuits may be determined or verified in a reliable and efficient manner.

In telegraphic systems wherein service is carried on over lines equipped for duplex operation and in situations where the amount of traffic is important and sufficiently heavy to require substantially all of the line time for the transmission operations, it will be readily apparent that any interruption of the line circuit will entail pecuniary loss as well as inconvenience. When multiplex telegraphic working is employed with such duplexed lines, the capacity and importance of the service is further increased, and additional measures directed to maintaining uninterrupted service on a line are accordingly warranted.

On duplexed lines, where the electrical condition of the circuit, particularly in the matter of its electrostatic capacity and insulation resistance, are subject to variation, as commonly experienced on so-called open wire lines, it is important that adjustments be made from time to time in the various parts of the artificial line portion of the equipment in order that a change of insulation on the line proper will not reach a point at which the telegraphic service would actually fail.

The present system is directed to means for readily verifying the condition of a duplex balance in a manner to meet the exactations of service as above pointed out, and comprises current indicating means and switching means whereby observations as to balance may be taken in substitution of a single channel or message period of a plurality of channels or message periods which collectively occupy the total time of a line circuit. The service features of the system further provide that for an unbalanced con-

dition, the indication given will correspond with the relation of the non-balance between a real line and an artificial line and also serve as a measure of the extent of such unbalance. Adjustments can therefore be readily made in the devices of the artificial line and the circuits brought to a proper balance without interrupting other of the channels working over the line.

This invention is illustrated diagrammatically in the accompanying drawing, and in order to avoid complexity therein, the telegraphic equipment shown includes only such devices and circuits as will be necessary to a clear understanding of the invention.

Referring to the drawing, the reference numeral 1 indicates a telegraph line which is connected serially through the windings of a polarized relay 2, and an artificial line AL to earth. A developed view of a single channel section or arm A of a sending distributor comprises a trailer brush 5 which is adapted to traverse a path formed by a collector ring section 6 and five contactor segments 4 adjacent thereto. It will be understood that a suitable telegraph transmitter (not shown), connected to the five segments 4, controls the combination of current impulses to be transmitted to line. Such combinations may be formed in accordance with the well-known five unit code of Baudot. In traversing its path, the brush 5 successively connects the segments 4 with the ring section 6, thereby completing a path for the transmitter currents by way of a conductor 7 to the apex or neutral point 8 of the duplexed line 1. From this point a portion of these currents traverse the left-hand winding of the polar relay 2, and the artificial line AL to earth, while a like portion of current traverses the right-hand winding of the relay 2, and the line circuit 1 to an earth connection at a distant station (not shown).

In addition to these duplex paths a portion of the current from the transmitting equipment also traverses a leak circuit extending from the conductor 7 by way of a conductor 9, a relatively high resistance unit 10 and the windings of a polarized switching relay 11 to earth. As well understood in the art, although the outgoing currents are neutralized and non-effective in the relay 2, they effect the operation of a similar relay at a distant station whereby the current impulses are translated by means

of suitable receiving equipment into a message record. The purpose of the relay 11 will be presently described.

A developed view of a receiving section 5 B of the distributor comprises a trailer brush 20 adapted to traverse a path formed by a ring section 21, five segments 25-29 and five segments collectively indicated as 30. At 22 five magnets correspond with the 10 selecting relays or magnets of a telegraph receiver, and a transfer switch 23 serves to switch the segments 25 to 29, either to respective ones of the receiver magnets 22 or to a common or bus conductor 24. The 15 seven blades of the transfer switch are adapted to be moved together and when in the position shown they establish circuits whereby the condition of balance on the duplex circuits may be ascertained.

20 In order that the features of this invention may be more readily understood, a description thereof will be further preceded by a brief description of the operations by which messages are received from the distant station. Accordingly, let it be assumed that the transfer switch 23 is first moved to its right-hand position, whereby the receiver equipment 22 is connected with the receiving section B of the distributor. In- 25 coming impulses from the line 1 traverse the windings of the line relay 2, over the circuit already traced, thereby rocking the armature of this relay to engage one or the other of its oppositely positioned contact 30 stops, depending upon the polarity of the incoming impulses. A translating circuit may therefore be traced from a battery 3 over the armature of the relay 2 by way of a conductor 31, contacts 32 of the switch 23, a conductor 33 to the ring section 21, from which point the circuit is successively established by the brush 20 with the receiving segments 25-29. The purpose of the five segments 30 will be presently de- 35 scribed. From the segments 25-29, the circuits extend through the respectively associated right-hand contacts of the switch 23 to the receiving equipment 22.

It will be understood that an arrangement (not shown) is to be employed for maintaining a synchronous relation between incoming impulses from the line 1 and the arrival of the brush 20 over corresponding ones of the segments 25-29. In response 40 to impulses from the line 1, the relay 2 is therefore operated to selectively establish the battery 3 with the receiving section of the distributor which, in turn, includes such current changes to control the receiving equipment 22, as well understood in the art.

In tracing the various steps in the balance verifying operations, let it first be assumed that the switch 23 is moved to the position in which it is shown, and that a 45 transfer switch (not shown) at the distant

station is also moved to a position to substitute ground connection for a transmitter equipment to five segments of a transmitting distributor arm or section, through which messages are regularly sent to the receiver equipment 22. A branch circuit may now be traced from the line 1, over a conductor 34, contacts 35 of the switch 23 and the conductor 33 to the ring section 21. To meet this connection a second branch 50 circuit extends from a point intermediate the line relay 2, and the artificial line AL by way of a conductor 12, the armature 13 of the polar relay 11, from which point the circuit may continue either over the contacts 14 of this relay and a first winding 17 or over the contacts 15 of this relay and a second winding 18 of a current indicator 16 to a conductor 36, thence over contacts 37 of the switch 23, to the bus conductor 24, 55 common to the five segments 30, and also connected through five respective contacts of the switch 23 with the segments 25-29. The circuits just traced connect the current indicator 16, which may be in the form of 60 a ballistic galvanometer, in series with the brush path of the receiving distributor section B in bridge around the winding of the line relay 2. The transmitter assumed to be included with the distributor arm A 65 continues the sending of regular message impulses outwardly over the line 1, and through the leak circuit, these impulses rock the armature 13 of the relay 11 to one side or the other, depending upon their polarity. At the galvanometer 16 a needle 19 is moved 70 by negative current through its coil 17 in the same direction that it would be moved by positive current through its coil 18, and vice versa. When the duplex equipment is 75 properly balanced, the ohmic resistance, inductance and electrostatic capacity of the artificial line AL is of course equal to the corresponding electrical characteristics of the line 1, as routed through a similar duplex equipment at the distant station. Under such balanced condition, outgoing 80 impulses from the distributor arm A will not result in a difference in potential between the external terminals of the relay 2. Therefore, as the brush 20 in its regular 85 travel connects the ring 21 with the segments 25-29 and 30, no current will flow through the galvanometer 16. In case the duplex equipment is out of balance, however, a difference of potential will be established by the outgoing impulses at the terminals of the relay 2, and therefore, each time the brush 20 sweeps over the section B, such difference of potential will move the 90 needle 19 of the galvanometer 16. For convenience of description it may be assumed the connections are such that for a condition of unbalance, caused by the resistance of the line 1 being lower than the resist- 95

5
ance of the artificial line, the galvanometer
needle will move to the left, and when the
artificial line is of lower resistance than the
line 1, the needle will be deflected to the
left, the degree of unbalance being indicated
by the range or amplitude of the deflection
of the needle.

10
For the purpose of further illustration, let it be assumed that the apparent resistance
of the line 1 has been diminished, say, through a change from dry to wet weather, and let it be further assumed that a sequence
15 of five alternate positive and negative impulses are impressed on the segments of the distributer section A, beginning with a negative impulse. Since the brush 20 travels from left to right, in phase with the brush 5, the first impulse transmitted will move
20 the armature of the leak relay 11 to its negative position, as shown, at the same instant that the brush 20 completes the relay bridging circuit of the galvanometer on the relay 2, by connecting the ring 21 with the segments 25. A portion of the transmitted
25 negative impulse will, therefore, act through the circuit already traced from the artificial line side of the relay 2, through the galvanometer coil 17 to the line conductor 1. The next or positive impulse transmitted from
30 A will bias the armature of the switching relay 11 to its positive side, whereupon a portion of the transmitted positive impulse will flow from the artificial line side of the relay through the coil 18 of the galvanometer and the brush 20, now at segment 26, to the line 1. In a corresponding manner
35 the last three impulses will alternately act through the coils 17 and 18 of the galvanometer, but the needle 19 will be moved in
40 the same direction by each impulse, due to the connected relation of these coils, as already described. Since the direction in which the needle 19 is deflected in the present example would indicate to an attendant
45 that the resistance of the artificial line was higher than the resistance of the line 1, the adjustable devices (not shown) of the artificial line may be varied to such point that the needle 19 of the galvanometer 16 will
50 remain at its central or zero position and not be affected by message impulses which continue to be transmitted from A to the line 1.

55 The period of contact by the brush 5 on each segment at A is substantially equal to the period the brush 20 covers a regular receiving segment, as the segment 25, at B and an adjacent one of the segments 30, and since all of the segments at B are joined by
60 the switch 23 during the time it is in position for the verifying of balance, circuit at A is completed through the galvanometer during the full period of each impulse from the transmitting section A.

65 Since change to the balance just described

was assumed to have been necessitated through a change from dry to wet weather, it will be obvious that on the weather clearing and the line drying, its insulation resistance would increase, and in order that 70 service may not be interrupted from unbalance of the duplex circuits, the balance verifying galvanometer may again be switched into circuit and the artificial line readjusted to a higher resistance to balance 75 that of the line.

From the foregoing description, it will be clear that, for a duplex-multiplex equipped line in which the distributers are divided into quadrants, each of which are 80 provided with sending and receiving sections, quadruplex service, or four messages in each direction, or eight channel capacity, may be handled thereover. Since the balancing operations in accordance with the 85 present invention require that only a single channel or one-way one-message time of the line be interrupted, this would be equal to one-eighth of the total message time of such a line. In the same ratio only one-twelfth of the message time of a line would be consumed during the verifying and correcting of duplex balance on a sextuplex or 90 twelve channel duplex-multiplex equipped line. 95

What is claimed is:

1. In a system of duplex-multiplex telegraphy, a real line, an artificial line, distributer means, a relay connected to form a leak circuit and responsive to currents therein, 100 current indicating means, switching means for rendering a section of said distributer means ineffective for telegraphing, and circuits jointly controlled by said relay and said section of the distributer to connect 105 the indicating means for comparing the condition of electrical balance between said real and artificial line.

2. In a system of duplex telegraphy, a real line, an artificial line, distributer means included with said lines, current indicating means, switching means for connecting said current indicating means with said distributer, a relay responsive to message currents in said lines, and means controlled 110 by said relay for completing the circuit of said current indicating means whereby the electrical constants of said real and said artificial line may be compared. 115

3. In a system of duplex telegraphy, a main line, an artificial line, means for transmitting signals over said main line, means comprising a plurality of controlling circuits for indicating the presence of current, switching means for connecting said 120 indicating means with said main line, and a relay operated by the signals transmitted to said lines to control the inclusion of respective ones of the controlling circuits of said indicating means with said artificial line in 125 130

order to determine whether said main line and artificial line are in electrical balance one with the other.

4. In a system of duplex telegraphy, a real and an artificial line, means for signaling over said real line, a distributor, means for indicating the strength and direction of currents, switching means for connecting said indicating means to said real line by way of said distributor, and relay means controlled by telegraphic signals transmitted to said lines for extending a connection from said artificial line to said indicating means to verify the condition of electrical balance of said real line and said artificial line one with another.

5. In a system of multiplex telegraphy, a real line, an artificial line, a plurality of telegraphic equipments, means for signaling over said real line, distributor means for successively including said lines with said telegraphic equipments, a relay means responsive to message currents in said lines, a current indicating means, and means for transferring the control of said distributor from a single one of said telegraphic equipments to act co-operatively with said relay means in successively connecting said indicating means to become responsive to signaling currents in case the real line and artificial line are not in electrical balance one with the other.

6. In a system of duplex telegraphy, real and artificial lines, means for working telegraphic signals over said lines, distributor means for controlling said telegraphic signals, relay means operated by message currents in said lines, current indicating means, and switching means for rendering said relay means and said distributor means effective to establish said indicating means to indicate whether the electrical constants of said real line correspond with the electrical constants of the artificial line.

45 7. In a system of duplex telegraphy, real and artificial lines, means for working telegraphic signals over said lines, distributor means for transmitting signals outwardly over said real line, distributor means for receiving incoming signals from said real line, a relay responsive to the signals transmitted to said lines, current indicating means, and switching means to transfer the control of said receiving distributor from the reception of incoming signals to act jointly with said relay in connecting said indicating means between said real and artificial lines to indicate whether said lines are electrically balanced one with another.

60 8. In a system of duplex telegraphy, a main line, an artificial line, means for signaling over said main line, distributor means comprising a plurality of sections for respectively controlling the transmission and reception of signals, means provided

with a plurality of controlling circuits for indicating the strength and direction of currents, switching means for extending connections from said indicating means to said main line by way of said distributor means, and a relay operated by outgoing message impulses in said lines to control the inclusion of respective ones of the circuits of said indicating means with said artificial line in phase with changes in the polarity of said transmitted signals for indicating whether said main line is in electrical balance with said artificial line or in which relation they may be out of balance.

9. In a system of duplex telegraphy, real and artificial lines, several transmitting and several receiving equipments for signaling over said lines, first distributor means for successively including said lines with said telegraph transmitter equipments, second distributor means for successively including said line with said telegraph receiving equipments, current indicating means, switching means for substituting said current indicating means for one of said telegraph receiving equipments, relay means controlled by transmitted signals to establish said indicating means to determine the condition of balance between said real line and said artificial line, and means controlled by said switching means to render the intervals of successive contacts on the portion of the distributor controlled thereby to have a period of contact equal to the period of successive contacts on said first distributor means.

10. In a system of duplex telegraphy, a real line and an artificial line, impulse receiving means connected with said real and artificial line, several telegraph receivers, a receiving distributor for successively including said impulse receiving means with said telegraph receivers, a plurality of telegraph transmitters, distributor means for successively connecting different ones of said transmitters with said real and artificial lines at such point thereof as will render transmitted impulses thereto ineffective with said impulse receiving means, relay means responsive to message impulses transmitted to said lines from one of said transmitters, means for indicating the direction and strength of currents, switching means for substituting said current indicating means for one of said receivers, and means controlled by said relay means to establish said indicating means to indicate whether the electrical characteristics of said real line are the same as the electrical characteristics of said artificial line, or in case they are not equal in what respect they are unbalanced.

In witness whereof I hereunto subscribe my name this 16th day of November, A. D. 1917.

JOHN H. BELL.
